HIS ATTORNEY.

UNITED STATES PATENT OFFICE.

FRED C. MARCH, OF WARREN, OHIO, ASSIGNOR TO GENERAL ELECTRIC COMPANY, A CORPORATION OF NEW YORK.

PACKING FOR INCANDESCENT-LAMP BULBS AND THE LIKE.

1,212,793.

Specification of Letters Patent. Patented Jan. 16, 1917.

Application filed April 7, 1913. Serial No. 759,400.

To all whom it may concern.

Be it known that I, FRED C. MARCH, a citizen of the United States, residing at Warren, county of Trumbull, State of Ohio, have invented certain new and useful Improvements in Packing for Incandescent-Lamp Bulbs and the like, of which the following is a specification.

My invention relates to the packing of incandescent lamps and lamp bulbs and the like, and besides being capable of affording efficient general protection against breakage and against shock which in the case of lamps might result in injury to the filaments, it is peculiarly adapted to the protection of the bowls and the tips of such articles.

Various additional advantages obtainable in connection with the invention will be come apparent from the description herein-after of certain particular forms of packing which embody it, these additional advantages including great simplicity and cheapness. However, while my invention extends to the particular embodiments which I shall herein show and describe and to their specific features and details, which are of importance on account of various specific advantages, yet it is not confined thereto, but can be otherwise carried out and applied.

In the accompanying drawings, Figure 1 is a somewhat conventional view of a lamp packing in which my invention is embodied. Fig. 2 is a similar view of a part comprised in the packing shown in Fig. 1. Fig. 3 is a partly sectional view indicating, in a somewhat conventional manner, how a number of incandescent lamps in the packing shown in Fig. 1 may be arranged in a container of a type commonly employed for incandescent lamps, a part of one of the packings being shown in longitudinal section in order that the lamp and its relation to the packing may be seen. Fig. 4 is a somewhat conventional view showing a lamp with a packing part of somewhat different character from that shown in Fig. 1. Fig. 5 is a similar view of still another form of packing.

As will at once be seen from Figs. 1 and 3, my invention resembles modes of packing previously in use to the extent that I employ a wrapper or jacket of any convenient and suitable material surrounding the large portion of the lamp bulb and extending

somewhat to each side of such portion. 55 When tubular wrappers or jackets of this general description and of the ordinary corrugated straw paper type are used to pack incandescent lamps, for example, according to previous practice, the lamps are merely 60 inserted in the wrappers or jackets (the jackets being thereby expanded where the largest portions of the bulbs come so that their corrugations are somewhat flattened, while the ends of the jacket assume the 65 conical form illustrated in Fig. 3), and some four or five of the lamps thus jacketed are packed side by side in a card-board carton such as is shown in Fig. 3, alternate lamps being base upward and the rest tip upward. 70 While the resulting package is reasonably good, it nevertheless has the disadvantage that in consequence of careless packing or of shifting of a lamp in its jacket the "tip" of a lamp (or the bowl of a "tipless" lamp) 75 not infrequently lies against the top or the bottom of the box, where it is exposed to almost the full impact of any blow that the box may receive, or that the tip even penetrates the cardboard of the box so as to be 80 in danger of being broken off by jar or shock endwise or sidewise of the box or by one box sliding over another, etc.

According to my invention, all danger of initial placing of the lamp in an improper 85 position in the packing or of its taking up an improper position is entirely obviated by making the packing resist movement of the lamp toward the end of the packing at which the "tip" end or bowl of the bulb lies, 90 either yieldingly or absolutely. This may be effected by contraction or reduction in any way of the portion of the jacket through which the lamp must move in this 95 direction, particularly by providing in this portion of the jacket some sort of obstacle which reduces the effective area available for such movement, or by spacing means associated with the jacket and interposed between the bowl of the lamp bulb and the adjacent wall of the container in which it is packed,—any of which forms of resistance may be of a more or less yielding character and can perfectly well be incorporated or employed in a jacket or wrapper which is 105 itself yielding,—or, in the case of a jacket which is yielding throughout its length, for example, by accentuation or reinforcement

of the resistance to expansion of the portion of the jacket through which the lamp must move toward the end at which the tip lies.

In the packing shown, the jacket or wrapper 1 as a whole comprises an ordinary corrugated tubular or cylindrical sleeve part 2 such as would prior to my invention be used for the lamp 3 to be packed, and all the modes of action mentioned above are present. For a straight sided 25 watt 110 volt Mazda incandescent lamp whose maximum diameter is about $2\frac{3}{8}$ inches and whose overall length is about $5\frac{1}{4}$ inches, as at present commercially manufactured, for instance, a jacket of this sort may be about $5\frac{3}{8}$ inches long and may have a diameter when unexpanded of about $2\frac{1}{8}$ inches, and may be corrugated to such an extent that if the corrugations were completely flattened its diameter would be, say, from 30% to 40% greater than this. As shown, the desired action of the jacket 1 as a whole is secured by means of a paper band or sleeve part 4 arranged at the end 5 of the jacket part 2 where the bowl 6 of the lamp bulb lies, this band being put in place either before or after the lamp 3 is inserted in the jacket 2, and being preferably placed inside the jacket 2 rather than outside it. It is not necessary to paste or otherwise secure the band 4 in place: it may simply be left loosely telescoped in the jacket 2.

The band part 4 shown in Figs. 1, 2 and 3, it will be seen, is corrugated like the jacket part 2 with which it is used. This band 4, furthermore, is prior to insertion therein of about the same diameter as the jacket 2 and is corrugated to about the same extent, and its width is slightly greater than the distance from the plane at about 7 where the lamp 3 is of greatest diameter to its tip 8. Such a band may consist of a portion of a jacket like that with which it is used, and for a 25 watt lamp such as above mentioned it may then be about $1\frac{1}{4}$ inches wide. Even though this band or sleeve part 4 be so inserted in the wrapper or jacket part 2 that the corrugations of the jacket part and those of the band part exactly coincide, as shown in Fig. 1, so that it becomes in effect a liner, its presence will keep the tip 8 or the bowl 6 of the lamp 3 at a safe distance from any surface against which the corresponding end 5 of the jacket part 2 lies. Moreover, the action is such that the lamp 3 is, in effect, resiliently supported or suspended in the jacket 1,—so that if, for example, one places the end 5 of the jacket 1 on a table and presses on the lamp base 9 so as to push the lamp forcibly down in the jacket 1 until the tip 8 comes in contact with the table, the lamp 3 will jump back away from the table as soon as it is released. What with this and the corrugations of the jacket 1, therefore, the lamp 3 is completely protected

against shock in any direction as well as against any ordinary blow upon the package 10 containing it.

If more positive protection for the tip of the lamp is desired, the band part may be made so as to be incapable of expanding enough to allow the bulb to actually pass through it; and if resilience is not thought important, a plain and entirely unyielding band 4^a of this character such as is shown in Fig. 4 may be employed,—such a band rendering it absolutely impossible for the lamp 3 to move too close to the end of the jacket or wrapper 1 unless sufficient force to burst the band is brought to bear.

Very positive protection for the tip of the lamp combined with more or less resilience can be obtained by using a relatively thick but freely expansible packing part such as is exemplified in Fig. 5. The sleeve part or band 4^b here shown, it will be seen, consists of a composite strip comprising a corrugated piece 11^b having a plain facing 12^b pasted or glued on one side of the corrugations. While almost any materials may be used, a corrugated piece of straw paper like that of the jacket 2 with a facing of the paper known as "chip" is cheap and satisfactory. As shown, the strip 4^b is of the same width as the sleeve or band 4 of Fig. 2 (say $1\frac{1}{4}$ inches for a 25 watt lamp such as above mentioned) and of such a length that when it is put in place in the end of the wrapper or jacket part 2 its ends will not overlap. It is arranged with its plain faced side outward, so that its corrugations will not fall in those of the sleeve 2, and thus it will always offer a very considerable obstacle to movement of the tip end of the lamp toward the corresponding end of the part 2. When this form of packing is used, the expansion of the part 4^b which movement of the lamp toward the end of the jacket part 2 at which its tip lies would necessitate will be yieldingly but effectually resisted by the resistance of this end of the jacket to expansion. This form of packing part and that shown in Fig. 4 give rise to advantages that may make them in many respects preferable to that shown in the other figures,—especially for lamps larger than the 40 watt tungsten lamp of the multiple type, for example.

What I claim as new and desire to secure by Letters Patent of the United States, is,—

A packing for incandescent lamp bulbs comprising a cylindrical corrugated wrapper adapted to be expanded and distorted out of its cylindrical form by the bulging portion of the lamp bulb upon insertion thereof and a single reinforcing ring of expansible material adapted to be inserted in one end of the wrapper to reduce the area thereof and to be engaged by the tip end of the bulb and expanded thereby to conform to the

shape of the interior of the wrapper and lamp bulb, whereby said ring is maintained in a definite position by the gripping action between said ring and wrapper to support and suspend the lamp bulb against accidental movement in the wrapper during handling.

In witness whereof, I have hereunto set my hand this 3rd day of April, 1913.

FRED C. MARCH.
